[57] ABSTRACT

A hydraulic or pneumatic aggregate wherein an end

face of the rotor defines a control gap with the annular control face of a thrust member which is movable axially in a one-piece cover of the housing and defines with the housing inner and outer annular pressure chambers wherein the fluid acts to urge the control face toward the end face of the rotor. The thrust member has a control portion which is provided with the control face and has an end face adjacent to the outer pressure chamber, an eccentric intermediate portion having an end face which is adjacent to the inner pressure chamber, a third portion which is coaxial with the control portion, and first and second passages which respectively extend between the control face and the end faces of the control portion and intermediate portion. The control face has first and second fluid pressure zones which respectively include the ends of the first and second passages, and the end faces of the control portion and second portion respectively have third and fourth fluid pressure zones. The distances between the centers of first and second zones and the axis of the control portion respectively equal or closely approximate the distances between the axis of the control portion and the centers of the third and fourth zones. This reduces the likelihood of overheating of the aggregate due to direct contact between the control face and the rotor and is achieved by appropriate selection of the diameters of the three portions of the thrust member, the eccentricity of the second portion, the outer diameter of the control face and the configurations of the ends of first and second passages in the control face.

THRUST MEMBER FOR FLUID-OPERATED ROTARY AGGREGATES

BACKGROUND OF THE INVENTION

The present invention relates to improvements in hydraulic or pneumatic aggregates in the form of pumps, motors, compressors, transmissions or the like. More particularly, the invention relates to improvements in aggregates of the type disclosed in my U.S. Pat. No. 3,561,328 entitled "Rotary Piston Machine." Still more particularly, the invention relates to improvements in the housing, rotor and especially the thrust member of a radial piston machine or the like.

My U.S. Pat. No. 3,561,328 discloses an aggregate wherein an end face of the rotor is adjacent to a control face provided on a thrust member which is non-rotatably mounted in the housing and is movable axially of the rotor. The end face of the rotor is provided with channels which sweep along fluid inlet and outlet ports in the control face of the thrust member. The latter has an eccentric portion which is spaced apart from the control face and is adjacent to one of two pressure chambers which are defined by the housing and the thrust member. Each pressure chamber communicates with one of the ports in the control face. The fluid in the pressure chambers urges the thrust member axially toward the end face of the rotor to thus determine the width of the control gap between the rotor and the thrust member.

A drawback of presently known aggregates of the just outlined character is that the control face of the thrust member is likely to engage the adjacent end face of the rotor in response to increasing fluid pressure and/or in response to increasing RPM of the rotor. This causes jamming, overheating and excessive wear upon the rotor and thrust member. My aforementioned U.S. Pat. No. 3,561,328 proposes the provision of a so-called opposition chamber which receives pressurized fluid and is intended to reduce the likelihood of actual contact between the rotor and the thrust member. It was found that such opposition chamber cannot always prevent an overheating and the resulting drawbacks, especially at high fluid pressures and at an elevated RPM of the rotor. In fact, the adjacent faces of the thrust member and rotor are likely to be heated to melting temperature. Moreover, the means for admitting pressurized fluid into the opposition chamber contributes significantly to the cost and bulk of the aggregate, and the provision of the opposition chamber necessitates the use of a reversing cylinder and piston for the thrust member. The provision of an opposition chamber necessitates the use of a relatively long thrust member with attendant increase in the bulk of the aggregate, as considered in the axial direction of the rotor. The reasons for overheating at elevated fluid pressure and/or at a high RPM of the rotor were totally unknown so that the presently known aggregates employing the aforesubjected thrust member have a rather limited utility.

SUMMARY OF THE INVENTION

An object of the invention is to provide a novel and improved thrust member which can be used in hydraulic or pneumatic aggregates as a superior substitute for conventional thrust members, which is less likely to cause an overheating of and/or other damage to the aggregate, and which is simpler, less expensive and more compact than heretofore known thrust members.

Another object of the invention is to provide a thrust member which can enhance the safety, reliability and effectiveness of the aggregate and can be installed in a one-piece part of the housing.

5 A further object of the invention is to provide a thrust member which is less likely to allow or cause an overheating of the aggregate than heretofore known thrust members even though the aggregate need not be provided with an opposition chamber, and which necessitates only minor changes in the design of heretofore known housings for aggregates in the form of hydraulic or pneumatic pumps, motors, compressors, transmissions or the like.

15 An additional object of the invention is to provide a hydraulic or pneumatic aggregate, such as a rotary piston machine, which embodies the improved thrust member.

20 Still another object of the invention is to provide the thrust member with a novel and improved control face and with novel and improved control and eccentric portions.

25 The invention is embodied in a hydraulic or pneumatic aggregate, such as a rotary piston machine, which comprises a housing having a socket (this socket is preferably provided in a one-piece portion of the housing), a rotor which is mounted in the housing and has a face facing the socket and provided with several channels for the flow of a fluid, and a novel and improved thrust member or distributor which is mounted in the socket and is movable axially of the rotor. The thrust member has a disk-shaped control portion provided with a control face which is adjacent to the face of the rotor, a cylindrical peripheral surface and a first end face facing away from the control face; a disk-shaped intermediate portion which is adjacent to the first end face, which is eccentric with respect to the control portion and which has a second cylindrical peripheral surface and a second end face facing away from the control portion; and a third portion which is adjacent to the second end face, coaxial with the control portion and has a third cylindrical peripheral surface. All three peripheral surfaces are sealingly received in the housing and the latter defines with the thrust member first and second annular pressure chambers which are respectively adjacent to the first and second end faces and receive fluid which urges the control face toward the face of the rotor. The thrust member is further provided with a first passage extending between the control face and the first end face and a second passage extending between the control face and the second end face. The control face has first and second pressure fluid zones respectively including the ends of the first and second passages in the control face, and these zones respectively comprise first and second centers located at predetermined distances from the axis of the control portion. The first and second end faces respectively have third and fourth pressure fluid zones whose centers are also located at predetermined distances from the axis of the control portion.

30 40 45 50 55 60 65 In accordance with a feature of the invention, the diameter of the three peripheral surfaces, the eccentricity of the second portion of the thrust member, the outer diameter of the (preferably annular) control face and/or the configurations of the ends of the first and second passages in the control face are such that the distances between the axis of the control portion and the first and second centers respectively equal or

4. The surfaces 6, 7, 8 are received in the cover 11 with minimal clearance and may but need not be provided with plastic sealing elements. The thrust member 1 is movable axially in the cover 11. As mentioned before, the inner pressure chamber 10 is bounded by the end face 22 and cylindrical surfaces 7 and 8, and the outer pressure chamber 9 is bounded by the end face 21 and the cylindrical surfaces 6 and 7. In addition, the chambers 9 and 10 are bounded by the adjacent radial faces and cylindrical internal surfaces of the cover 11.

FIG. 5 further shows that the thrust member 1 seals the pressure chambers 9 and 10 from the rotor 14 of the aggregate, as considered in the direction of the axis 43. The outer pressure chamber 9 is connected to a first conduit 12 for pressurized fluid, and the inner pressure chamber 10 is connected with a second conduit 13 for pressurized fluid. The conduits 12, 13 are shown in the form of channels machined into the cover 11. The fluid which enters the outer chamber 9 exerts pressure against the rear end face 21 and urges the control face 5 of the control portion 2 toward the adjacent rotating end face 57 provided on the rotor 14 or on a control ring 16 which rotates with and can be said to form part of the rotor 14. The fluid which enters the inner chamber 10 exerts pressure against the end face 22 of the eccentric portion 3 and thus urges the control face 5 toward the face 57 of the rotor 14 or control ring 16.

A control gap 58 is maintained between the face 57 of the rotor 14 or ring 16 and the control face 5 of the control portion 2. This gap can constitute a narrow clearance between the faces 5, 57 or these faces may be held in actual contact with each other. In accordance with the presently prevailing opinion in the art to which the present invention belongs, the fluid enters the control gap 58 by way of the passages 35, 36 and its pressure decreases to zero in a direction toward the inner and outer edges of the control face 5. The drop of fluid pressure in directions from the ports in the control face toward the inner and outer edges is believed to be linear or to resemble a slightly arching curve.

The rotor 14 is provided with axially parallel channels 15 which communicate with fluid displacing chambers 17 so that the fluid can leave the channels 15 by way of the respective chambers 17. These chambers receive radially movable fluid displacing elements 18 each of which can change the effective volume of the respective chamber 17. The rotor 14 is mounted on a thrust bearing (e.g., a pressure fluid bearing or a roller thrust bearing 20) and rotates in one or more radial antifriction bearings 19 so that its axis coincides with or is very close and parallel to the axis 43 of the portions 2,4 of the thrust member 1. The configuration of the channels 15 is shown in FIG. 4; these channels are provided in the control ring 16 and communicate with fluid displacing chambers 17 in the rotor 14 if the aggregate employs a control ring.

FIG. 1 shows that a portion of the peripheral surface 7 may extend radially outwardly beyond the edge 44 of the control face 5 but not beyond the peripheral surface 6. FIG. 2 shows that the areas of ports (edges 37,38) in the control face 5 are larger than the cross-sectional areas of the remaining portions of the passages 35,36.

For calculation of the pressure fluid field in the control gap 58, it is now assumed that the fluid pressure at the ports in the control face 5 of the control portion 2

is identical all the way between the circles 77 and 78 shown in FIG. 2. The circle 78 bounds an area whose radius is somewhat smaller than the radius of the circular outer edge 44 of the control face 5. The radius R_i of the circle 77 is somewhat greater than the radius of the inner edge of the annular control face 5. The radius R_o of the circle 78 is somewhat greater than distances between the axis 43 and the radially outermost portions of the edges 37,38 bounding the ports in the control face 5. The radius R_i of the circle 77 is slightly smaller than the distances between the axis 43 and the radially innermost portions of the edges 37,38. The exact diameters of the circles 77,78 can be readily determined by simple experimentation. Heretofore, it was believed that the circle 77 extends substantially midway between the inner edge of the control face 5 and the innermost portions of the ports (edges 37,38). It has been found that such assumption is inaccurate, especially if the control gap 58 is very narrow or when the width of this control gap is reduced to zero.

As regards the diameter of the circle 78, it was assumed heretofore that this circle extends substantially midway between the outer edge (44) of the control face 5 and the edges 37, 38 bounding the ports in the control face. Such assumption, too, has been found to be inaccurate, especially when the distance between 37,38 on the one hand and 44 on the other hand is substantial and/or when the control gap 58 is narrow or is reduced to zero. Consequently, it is considered desirable to place the ports in the control face 5 as close as possible to the outer edge 44 and as close as possible to the inner edge of the control face; for example, the distance between 37,38 and 44 may be in the range of 2-6mm or 1/20 - 1/5 inch. This insures that the diameters of the circles 77,78 deviate only slightly from an ideal value, i.e., the uncertainty concerning the exact location of these circles is reduced to a minimum to thus allow for a more accurate calculation of fluid pressure fields in the control gap 58. If the distance between 37,38 and 44 is very small (e.g., 2 millimeters, the circle 78 can be assumed to pass midway between 44 on the one hand 37,38 on the other hand. However, this holds true only if the just discussed distance is very small; otherwise, such assumption regarding the position of the circle 78 can lead to gross miscalculations of pressure fluid fields in the control gap 58.

As mentioned before, the fluid pressure zones including the two ports in the control face 5 and the surrounding portions of this control face include two centers 31 and 32 whose distance from the axis 43 is respectively G_{co} and G_{ci} . The cross-sectional area A of the fluid pressure zone including the port forming part of the passage 35 is calculated as follows:

$$A_{stz} = (R_o^2 - R_i^2)\alpha\pi/4 \times 360 \quad (1)$$

The cross-sectional area of the fluid pressure zone including the port forming part of the passage 36 is calculated in the same way as A_{stz} i.e., with the help of the equation (1).

The force F which tends to move the thrust member 1 axially and away from the rotor 14 (i.e., the pressure which acts upon the control face 5 of the control portion 2 and upon the face 57 of the control ring 16 or rotor 14) can be calculated by multiplying the result of

the equation (1) with fluid pressure p in the control gap 58. Thus,

$$F_{Stz} = A_{Stz} \times p$$

The pressure in the control gap 58 is only one of those factors which influence the reliability of the thrust member 1. It is further necessary to determine the distances Gco and Gci . These distances are calculated as follows:

$$Gc = [2(Ro^3 - Ri^3)/3(Ro^2 - Ri^2)] \times [(\sin \alpha_2 - \sin \alpha_1)/(\alpha_2 - \alpha_1)]$$

(3) 15

The meaning of α will be understood by referring to FIG. 2.

If the areas of the ports in the control face 5 (see the edges 37,38 in FIG. 2) are not enlarged in accordance with the present invention, Gco equals Gci , i.e., each of these distances equals the distance Gc in the equation (3).

In order to insure that the thrust member 1 will be urged toward the rotor 14 or control disk 16 with a requisite force (but not with an excessive force), the cross-sectional areas of the pressure chambers 9 and 10 preferably exceed somewhat the cross-sectional area A_{Stz} according to the equation (1). Satisfactory dimensioning of pressure chambers 9 and 10 can be achieved in accordance with the equation

$$A_{Dfk} = A_{Stz} \times fb$$

(4)

wherein the factor fb is preferably 1.04-1.06. In certain specific instances, the factor fb will deviate from the above range.

Deviations of the cross-sectional area of chambers 9,10 from the just discussed area will result in overheating of the faces 5 and 57 or in excessive leakage of fluid from the control gap 58. Such leakage will greatly affect the efficiency of the aggregate.

By considering the equation (4), the dimensions of the outer pressure chamber 9 can be calculated as follows:

$$(ro^2 - rm^2)pi/4 = [(Ro^2 - Ri^2)\alpha \times pi/4 \times 360] \times fb$$

(5)

The dimensions of the inner pressure chamber 10 can be calculated as follows:

$$(rm^2 - ri^2)pi/4 = [(Ro^2 - Ri^2) \alpha \times pi/4 \times 360] \times fb$$

(6)

The values of ro , ri and rm are shown in FIG. 3.

If the aggregate is to operate safely and with a high degree of efficiency, the distances gco and gci should respectively equal or closely approximate Gco and Gci . Thus, the distances gco and gci must be calculated with a high degree of accuracy. This can be achieved by resorting to the equations

$$g_{eo} = \int \frac{\theta \pi}{540} \left[\left(r_o - \frac{e^2}{4r_o} + \frac{e \sin \alpha}{\text{arc } \theta} - \frac{e \sin (\alpha - \theta)}{\text{arc } \theta} \right) \right. \\ \left. + \frac{e^2 \sin 2\alpha}{8r_o \text{arc } \theta} - \frac{e^2 \sin 2(\alpha - \theta)}{8r_o \text{arc } \theta} \right)^3 - r_m^3 \left] \cos \left(\alpha - \frac{\theta}{2} \right) da / \bar{K}_1 \right]$$

(7)

and

$$g_{ei} = \int \frac{\theta \pi}{540} \left[\left(r_m - \frac{e^2}{4r_m} + \frac{e \sin \alpha}{\text{arc } \theta} - \frac{e \sin (\alpha - \theta)}{\text{arc } \theta} \right) \right. \\ \left. + \frac{e^2 \sin 2\alpha}{8r_m \text{arc } \theta} - \frac{e^2 \sin 2(\alpha - \theta)}{8r_m \text{arc } \theta} \right)^3 - r_i^3 \left] \cos \left(\alpha - \frac{\theta}{2} \right) da / \bar{K}_1 \right]$$

(8)

wherein

$$10 \bar{K}_i = (r_o^2 - r_m^2 / 2(n-1)) \text{ resp. } \bar{K}_i = (r_m^2 - r_i^2) / 2(n-1)$$

(9)

The equations (7) and (8) are explained in detail in my copending application Ser. No. 321,853, filed Jan. 8, 1973.

Since the equations (7) and (8) cannot be readily integrated, it is advisable to proceed as follows: One forms a number of angular intervals τ and calculates for each thereof the values under the integral symbol. The thus obtained values are totalized and the sum is divided by $k1$, i.e., by the average value of the area of the respective pressure zone between the angular limits of an interval. For example, one can select τ to equal 10° and one can calculate between -5° and 185° . Thus, and referring to the equation (9), the median value of the area interval can be determined by dividing with $(n-1)$ wherein n is the number of measured intervals.

30 The diagram of FIG. 6 illustrates the values of gco and gci as a function of the eccentricity e of the portion 3. The horizontal line Gc represents the aforesaid distance between 41 or 42 and 43.

35 The configuration of the thrust member 1 is ideal if the calculation of distances gci and gco furnishes a value corresponding to the point where the curves of FIG. 6 intersect each other. This point is indicative of the proper eccentricity e of the portion 3. A thrust member with an eccentric portion 3 having the just discussed ideal eccentricity would prevent jamming or overheating or wear upon the faces 5, 57 and would further prevent excessive leakage through the control gap 58. However, it was found that the curves Gc , gco and gci of FIG. 6 normally do not intersect each other at a single point. In order to achieve at least substantial coincidence of the distances Gc and gco , my U.S. Pat. No. 3,561,328 proposes to employ the so-called opposition chamber and to select the diameter of the outer pressure chamber in such a way that it exceeds the outer diameter of the control face of the thrust member. At the time of conception of the invention which is disclosed in my U.S. Pat. No. 3,561,328, the distances Gc and gco were determined exclusively on the basis of experiments rather than by calculation. The 40 positions of the pressure fluid centers were estimated or were determined graphically, e.g., by planimetry of the pressure chambers and fluid pressure zones. Therefore, the thrust member of my U.S. Pat. No. 3,561,328 does not insure an absolutely reliable operation of the aggregate.

45 In accordance with another prior proposal which is disclosed in my Austrian Pat. application Ser. No. A57/72 and which followed the conception of invention disclosed in my U.S. Pat. No. 3,561,328, the aforementioned opposition chamber can be omitted if the eccentric portion of the thrust member extends in part beyond the outer edge of the control face. This was arrived at on the basis of calculations which indicated that the center of gravity of pressure fluid (gco) should be located outwardly of the center Gc so that a part of

the eccentric portion necessarily projected beyond the control face of the thrust member. This necessitated the use of a two-piece cover in order to render it possible to mount the thrust member therein. Such solution was quite satisfactory as regards the construction of the thrust member; however, the assembly and manufacture of a two-piece cover greatly increase the cost (especially the initial cost) of the aggregate. Thus, at the time of my aforesubmitted earlier proposal, it was not known in the art to use a one-piece cover and to thus employ a thrust member wherein the eccentric portion does not extend beyond the edge of the control face while at the same time insuring that Gc equals gc . This is achieved for the first time in accordance with the present invention which provides an aggregate wherein the thrust member can be installed in a one-piece cover because its eccentric portion 3 need not extend radially beyond the outer edge 44 of the control face 5. Such construction of the cover 11 and thrust member 1 contributes to the lower cost of the aggregate and is achieved by

- a. proper dimensioning of the aforementioned cylindrical peripheral surface 6 which seals the outer pressure chamber 9 at the radially outermost end thereof,
- b. proper dimensioning of the aforementioned cylindrical peripheral surface 7 which seals the pressure chambers 9 and 10 from each other,
- c. proper dimensioning of the cylindrical peripheral surface 8 which seals the inner pressure chamber 10 at the radially innermost part thereof, and
- d. special configuration of the control face 5, its ports (channels 35,36) and the diameter of its outer edge 44.

This insures that the fluid pressure zone centers 41,42 at the control face 5 and the fluid pressure zone centers 31,32 at the end faces 21,22 are respectively located on two common lines. Consequently, the distances Gc are identical with the distance gc and the intermediate portion 3 need not extend radially outwardly beyond the control face 5.

As shown in FIG. 1, the diameter of the cylindrical peripheral surface 6 at least equals but preferably exceeds the diameter of the outer edge 44 of the control face 5 on the control portion 2. In some instances, the diameter of the peripheral surface 6 can be made smaller than the diameter of the edge 44.

The feature (b) of the present invention contributes to equality of Gc and gc by properly selecting the diameter of the surface 7 relative to the surfaces 6,8 and by proper selection of the eccentricity e . As explained above, the eccentricity e will be selected by calculating the distances gc for different eccentricities. See the equations (7), (8), (9) and FIG. 6.

The aforementioned feature (c) includes the selection of the diameter of the surface 8, together with the diameter of the surface 6, in such a way that the distances gc equal the distances Gc at the control face 5. Once the radii of the cylindrical peripheral surfaces 6 and 8 are determined, the radius of the peripheral surface 7 can be calculated in accordance with the equation

$$r_m = \sqrt{\frac{1}{8}(r_o^2 + r_i^2)}$$

(10)

The feature (d) is also important in making the distances Gc equal to the distances gc . Thus, by increasing or reducing the diameter of the outer edge 44 of the control face 5 with respect to the diameter of the peripheral surface 6, one can change (increase or reduce) the distances Gc between the centers 41,42 of pressure zones at the control face 5 and the axis 43. Similar results can be achieved by changing the dimensions of the channels 15 in the rotor 14 or control ring 16 and/or by changing the dimensions of the ports (passages 35,36) in the control face 5, as considered in the radial direction of the thrust member 1.

If the outline of a channel 15 deviates from round (see FIG. 4), the outer diameter of the control face 5 can be reduced to thus allow for an increase or a reduction in the distances Gc . The inner diameter of the control face 5 is then reduced accordingly.

FIG. 6 shows that the distances gco and gci vary with changes in eccentricity e of the intermediate portion 3. Also, the distance gco does not change at the same rate as the distance gci . When the line representing the distance Gc does not intersect the curves representing the distances gco and gci at the exact point where the curve gco intersects the curve gci , it is still possible in accordance with the present invention to make the distance Gc equal to gco and gci to thus enhance the reliability of the thrust member 1. This is achieved by increasing the area of the one or the other port in the control face 5. Thus, if the distance Gc of the center 41 of the zone 35 including the port forming part of the passage 35 is less than the distance gci or gco , this port is increased radially outwardly. Inversely, the port is extended radially inwardly if the respective Gc exceeds gco or gci . Such extension of the port radially inwardly or radially outwardly brings about a change in the distance Gc . In other words, Gco need not be identical with Gci , as long as it equals gco and as long as Gci equals gci . It is clear that any widening of the ports in the control face 5 radially inwardly or outwardly should not be accompanied by changes in the configuration of channels 15 in the rotor 14 or control ring 16. In other words, the ports in the control face 5 should be extended radially inwardly or outwardly beyond the channels 15.

It is further within the purview of the invention to make the outer edge 44 of the control face 5 eccentric relative to the peripheral surface 6. Such eccentricity can be resorted to in order to insure that the distances Gco and Gci respectively equal the distances gco and gci .

An important advantage of the improved thrust member 1 is that it can be installed in a one-piece portion of the housing, that its cost is lower than the cost of conventional thrust members whose dimensions must be selected on the basis of extensive experimentation rather than by resorting to simple and reliable calculations, that it contributes to greater efficiency of the aggregate, that it can be used in aggregates wherein the fluid is maintained at an elevated pressure, that it can be used in aggregates wherein the rotor rotates at a high speed, and that its useful life (together with that of the rotor) is much longer than the useful life of conventional thrust members.

The greater efficiency, reliability and longer useful life of the improved thrust member are believed to be attributable to a number of factors including the reduced axial length of the thrust member. As explained before, the thrust member of my U.S. Pat. No.

3,561,328 is quite long due to the provision of an opposition chamber which is intended to prevent jamming and overheating. A relatively long thrust member has insufficient freedom of swiveling (spherical) movement so that its control face cannot remain exactly parallel to the end face of the rotating rotor. Another factor which is believed to contribute to greater reliability and usefulness of the improved thrust member is that the distances G_{co} and G_{ci} respectively equal or vary closely approximate the distances g_{do} and g_{ci} . In the thrust member of my U.S. Pat. No. 3,561,328, the provision of the opposition chamber cannot guarantee the identity of distances G_{co} and g_{co} or G_{ci} and g_{ci} . As a rule, the center of the zone wherein the fluid pressure is higher is located at a first distance from the rotor axis and the center of the zone wherein the fluid pressure is lower is located at a different second distance from the rotor axis. Therefore, the control face of the thrust member which is disclosed in the aforementioned patent does not float in exact parallelism with the adjacent end face of the rotor, i.e., the control face is tilted relative to the face of the rotor which often leads to localized contact between such faces with attendant overheating and melting which normally results in immediate destruction of or in substantial damage to the aggregate. It is clear that the tilting of the patented thrust member is extremely small (as determined by the accuracy of its mounting in the housing); however, even minor tilting suffices to bring about actual contact between the rotor and the thrust member will all of the aforesubussed consequences.

The just discussed drawbacks of the patented thrust member are avoided by constructing the improved thrust member 1 in such a way that it can be received in the socket of a one-piece housing portion (cover 11), by omitting the opposition chamber (which renders it possible to reduce the length of the thrust member and to simplify the construction of the housing), and by calculating (rather than estimating) the distances G_{co} , G_{ci} , g_{co} and g_{ci} .

As shown in FIG. 5, the maximum diameter of the pressure chamber 9 may exceed the maximum diameter of the control face 5. Also, the diameter of the peripheral surface 8 may exceed the minimum diameter of the control face 5. The control face 5 is flat, at least in the regions surrounding the ports therein. The cross-sectional area of the pressure chamber 9 and/or 10 may be 55-60 percent (plus minus 10 percent of the effective area of the control face 5. FIG. 7 shows, that the high pressure equivalent area of the control mirror (control clearance) extends from the radius 52 to the radius 53. The inner radius 52 is located substantially midway between the innermost extension of the control face and the inner wall of the control port 35 or 36. The outer radius 53 is located substantially midway between the outer end of the control face and the outer wall of the control port 35 or 36. The inner radius of the control face is shown at 74 and the outer radius of the control face is shown at 73. Radially beyond the peripheral surface 7 of the thrust member 1 has a radius 75 and extends beyond the control face. The angular interval of angle τ between the radii 52 and 53 spans an area $dF = 51$ which can be calculated by resorting to the equations of the specification. Radius 55 corresponds the radius r of one of the equations and the gravity or pressure centers of the control face are located at distances $G_c = 56$, from the axis of the rotor

and thrust member. These distances can be calculated by resorting to the equation (3).

FIG. 8 shows the distance $g_{co} = 59$ between the pressure center of the outer chamber and the axis of the rotor as well as the distance $g_{ci} = \alpha$ between the axis of the rotor and the inner thrust chamber. These distances can be calculated by resorting to the equation (7) or (8). For the understanding of the respective equations the integral median value radius $A = 61$ is shown in FIG. 8; this radius be calculated by resorting to the equations which follow. The eccentricity e of the thrust member portion 3 is indicated at 57; this eccentricity is an important factor in the following equations.

FIG. 11 shows a thrust member, which does not have an end portion 4, but only a first seat portion 71 and an eccentric second seat portion 69.

Such thrust member renders it possible to omit a third seal, and one of the thrust chambers. Since such thrust member is the shortest and the simplest at a first glance, attempts were made to determine the reliability and efficiency of such thrust member for tight seal of the control mirror with little friction.

However, since the invention provides that the pressure centers g_c must have the same distance from the axis of the thrust member as the distances G_c of the pressure centers of the control face thereof, it was found by utilizing the equations of this specification that such thrust member cannot be realized for efficient work without dividing it into several parts. Either the control face becomes too wide, or the seat 68 becomes bigger than the control face, so that the control body cannot be assembled without division. Therefore, the thrust member of FIG. 11 consists of two parts, namely a front part 70, which has the control ports 36 and 35 and an end part 71 which has the seat portion 68 and the eccentric portion 69. Seal grooves 67 are provided for the reception of O-ring seal means. The radial inward extension of the control face is limited by the bore or recess 71a.

By utilizing the equations of the specification, it was found that very high pressure or for very high accuracy of the identity of distances of the pressure centres G_c and g_{ci} and G_c and g_{co} , it is necessary to provide the end portion 62 (see FIG. 9) of the thrust member with a second eccentricity which is different from eccentricity of the shoulder 3.

FIGS. 9 and 10 show that the end portion 66 of the thrust member has a second eccentricity $e_2 = 63$, while its shoulder or median portion 3 has a first eccentricity $e_1 = 64$. O-ring seals 65 may be inserted into the respective seal grooves for making a somewhat larger clearance between the thrust chamber walls and the thrust member in order that the thrust member can move a little within its seats relative to the rotary control face of the rotor of the fluid handling device.

For many practical applications in fluid handling devices operating at fluid pressures of up to about 5,000 psi the second eccentricity can be spared and the end portion 66 can be made concentric because the second eccentricity would be very small according to the calculations by resorting to the equations of the specification.

The calculations show further, that, in order to satisfy the $G_c = g_c$ condition of the invention, the outer seat portion 6 of the thrust member must extend centrically beyond the outer face of the control face (outer diameter of the control face). And, further, the control face

must be limited radially inward by a recess or bore 98 shown in FIG. 9. The diameter of the end portion 66 must be bigger than the inner diameter of the control face. If these conditions are met and the basic condition of the invention, namely $Gc = gc$ is met, then the thrust member of the invention operates efficiently for a long period of time.

In order to achieve the desirable accuracy and thereby the efficiency and reliability of the thrust member, the values gc must be calculated with a high degree of accuracy.

The high pressure zone does not develop exactly along an arc of 180° of the control area 32, but actually along 180° plus 2 gamma, wherefrom it follows that

$$G = (180^\circ + 2\gamma)/360 \quad (11)$$

In the equation (11), gamma represents the constant value of the high pressure equivalent area. It is to be understood, however actually gamma is not constant but changes permanently during operation of the machine, depending you, how far a respective rotor passage extends beyond the control port 35 or 36 with which it communicates at the respective time. The constant value gamma is, therefore an average value for a given period of time. Depending on the size and configuration of the control area the value of gamma is normally between 0° and 15° .

With the above in mind the control area can be replaced for convenience of calculation by the high pressure equivalent area A_{HPm} which is determined as follows:

$$A_{HPM} = (r_o^2 - r_i^2) \pi G \quad (12)$$

After the high pressure equivalent A_{HPm} of the control area is known, it is easy to find the necessary cross-sectional area of the necessary fluid containing pressure chamber on the respective shoulder of the control body. The cross-sectional area A_{pc} of the respective pressure chamber is determined by multiplication of the high pressure equivalent area A_{HPm} with the balance factor fb as follows:

$$A_{pc} = A_{HPm}b = A_{HPm} \times fb \quad (13)$$

wherein the balance factor fb is commonly $1,056 \pm 0.2$ depending upon, how strongly the control body shall be pressed against the rotary control face and how strong the resisting frictional forces in the seals etc. are. Actually there are seals, like O-rings, provided between the respective seats in the housing and the respective portions of the thrust member. For high pressure devices such assumption would lead, as is recognized by this invention, again to local overstressing in one area of the control zone and to much lower pressures in the other zone of the control area because the pressure centers of the control area would not be located midway between r_i and r_o .

According to this invention, the pressure center of the high pressure equivalent area of the control area is located on the integral median value of the high pressure equivalent area of the control area.

Thus, according to this invention, the integral median radius rgc is introduced. By considering the area portion $dF = 51$ of FIG. 7, the integral median radius rgc is calculated as follows

$$r_{gc} = \int \frac{rdF}{F} = \frac{\theta\pi}{180} \frac{\int r^2 dr}{F} = \frac{\theta\pi}{180} \frac{(r_o^3 - r_i^3)}{3F} = \frac{360}{540} \frac{(r_o^3 - r_i^3)}{(r_o^2 - r_i^2)} = \frac{2(r_o^3 - r_i^3)}{3(r_o^2 - r_i^2)} = r_{gc} \quad (14)$$

However, the determination of the integral median value rgc of the integral median radius does not automatically lead to determination of the pressure center Gc of the control area. The pressure center of the high pressure equivalent area of the control area is located at the distance $Gc = 56$ from the axis of the respective thrust member.

For finding this important distance Gc the integral median value over the respective angle is to be calculated. This is achieved as follows:

$$G_c = \frac{\int_{\alpha_1}^{\alpha_2} r_{gc} d\alpha}{\alpha_2 - \alpha_1} = r_{gc} \frac{\int_{\alpha_1}^{\alpha_2} \cos \alpha d\alpha}{\alpha_2 - \alpha_1} = r_{gc} \frac{\sin \alpha_2 - \sin \alpha_1}{\alpha_2 - \alpha_1}$$

$\alpha = \text{in arcus values}$ (15)

If in this equation rgc equals 1, then a fixed curve appears over the angle area, which provides the factor fG . For the area 0° to 180° the factor fG is 0.636.

For actual calculation of the gravity center distance Gc the value fG is to be multiplied with the value rgc . Depending on angle gamma of equation (11) the value of fG varies between 0.4 and 0.7 for practical applications.

U.S. Pat. No. 3,320,897 discloses a method for calculating the median integral value A through a section through two circles of different radii r and R and an eccentricity e between the centers of both circles. However, since the inner and outer diameters of each of the pressure chambers form circles of different radii and both chambers have an eccentricity e , median value A see FIG. 8, reference character through the outer face of a sector of angle τ = reference character in FIG. 8, can be used for calculating the value A of the respective pressure chamber of the invention.

This median integral value A is calculated according to U.S. Pat. No. 3,320,897 as follows:

$$A = \frac{\int_{\alpha-\theta}^{\alpha} \left(e \cos \alpha + r_o - \frac{e^2}{2r_o} \sin^2 \alpha \right) d\alpha}{\alpha_1 - \alpha_0} \quad (16)$$

which reads after integration:

$$A = r_o - \frac{e^2}{4r_o} + \frac{e \sin \alpha}{\text{arc } \theta} - \frac{e \sin (\alpha - \theta)}{\text{arc } \theta} + \frac{e^2 \sin 2\alpha}{8r_o \text{arc } \theta} - \frac{e^2 \sin 2(\alpha - \theta)}{8r_o \text{arc } \theta} \quad (17)$$

Therein is to the outer radius of the respective pressure chamber or thrust-body portion. The angle τ is the angle of the calculated interval. An interval $\tau = 10^\circ$ or 5° is normally satisfactory for the calculation.

The eccentricity e corresponds to the desired pressure center distance $gc = 59$ for the inner pressure chamber and for the outer pressure chamber the eccentricity e in the equations corresponds to reference character 60 plus 5f of FIG. 8.

The next step is to calculate the cross-sectional area of the interval K_1 of FIG. 1 which is called K_1 in accordance with U.S. Pat. No. 3,320,897 and it is calculated as follows

$$K_1 = A^2 \pi \theta / 360 - R_1^2 \pi \theta / 360 \quad (18)$$

$$K_1 = \left\{ r_o - \frac{e^2}{4r_o} + \frac{e \sin \alpha}{\text{arc } \theta} - \frac{e \sin(\alpha - \theta)}{\text{arc } \theta} + \frac{e^2 \sin 2\alpha}{8r_o \text{arc } \theta} - \frac{e^2 \sin 2(\alpha - \theta)}{8r_o \text{arc } \theta} \right\} \frac{\pi \theta}{360} \quad (19)$$

From the values of K_1 the integral median value of K_1 is to be found in order to be able to calculate with the said median integral value K_1 . The median value of K_1 can be found by computing all calculated intervals of K_1 and by dividing the thus obtained sum by the number z of the intervals. This is calculated as follows:

$$\bar{K}_1 = \sigma K_1 / z \quad (20)$$

For determining the pressure center of the respective fluid containing pressure chamber it is necessary to calculate each pressure center of each section interval K_1 of the angle τ .

In this respect it is to be recognized in accordance with this invention, that the pressure center of the interval K_1 is not in the middle between the inner and outer seal faces because the outer part of interval K_1 is wider than its inner part. Consequently the pressure center of the interval K_1 is nearer to its radially outer end. It is therefore necessary to find the radius r_g on which the pressure center of the respective interval K_1 is located. The radius r_g is the radial integral median value through the cross-sectional area of the interval K_1 and is calculated as follows:

$$r_g = \int k_1 dr / \bar{K}_1 = \int A^2 - r_1^2 dr / \bar{K}_1 = \theta \pi (A^3 - r_1^3) / 540 \quad (21)$$

For further calculation, the product B_a which equals the interval area K_1 multiplied by the integral median value of r_g is to be found. The integral median value of r_g equals the median integral value of r_g multiplied by $\cos(\alpha - \theta/2)$. Thereby it is possible to eliminate K_1 as follows:

$$B_a = \Delta K_1 \bar{r}_g = \Delta K_1 \times \bar{r}_g \cos(\alpha - \theta/2) = \pi \theta / 540 (A^3 - r_1^3) \cos(\alpha - \theta/2) \quad (22)$$

The desired distance g_c of the gravity or pressure center of the fluid containing pressure chamber or $g_c + e$ of the pressure chamber from the axis of the rotor can now be found by calculating the integral over B_a divided by the integral median value over the intervals K_1 , as follows:

$$G_c = \int B_a / \bar{K}_1 \quad (23)$$

or:

$$g_c = \int \frac{\theta \pi}{540} \left[\left(r_o - \frac{e^2}{4r_o} + \frac{e \sin \alpha}{\text{arc } \theta} - \frac{e \sin(\alpha - \theta)}{\text{arc } \theta} + \frac{e^2 \sin 2\alpha}{8r_o \text{arc } \theta} - \frac{e^2 \sin 2(\alpha - \theta)}{8r_o \text{arc } \theta} \right)^3 - r_1^3 \right] \cos \left(\alpha - \frac{\theta}{2} \right) d\alpha / \bar{K}_1 \quad (24)$$

which leads to equations 7 and 8 for the inner and outer thrust chamber.

The very important final equation for finding the distance of the pressure center of the respective fluid containing pressure chamber or from the axis of the rotor or from the axis of the central portion(s) of the control body is not integrable without difficulties. It is however very convenient to calculate with it by calculating a number of intervals Z of it and thereafter to divide and thus obtained sum by the number of intervals Z , as far as the value above the fraction line is concerned. Thereafter the thus obtained value is to be divided by the median value of K_1 , which was obtained by resorting to the equation (9). Thereby the value g_c of the location of the pressure center of the respective fluid containing pressure chamber or $g_c + e$ is obtained with sufficient accuracy.

I claim:

1. In a hydraulic or pneumatic aggregate, a combination comprising a housing having a socket; a channeled rotor mounted in said housing said having a face facing said socket; and a thrust member mounted in said socket and movable axially of said rotor, said member including a control portion having an annular control face adjacent to said face of said rotor, a first end face facing away from said control face, and a cylindrical peripheral surface, an eccentric second portion adjacent to said first end face and having a second end face facing away from said control portion and a second cylindrical peripheral surface, and a third portion adjacent to said second end face and having a third cylindrical peripheral surface coaxial with said first peripheral surface, said peripheral surfaces sealingly engaging said housing and said member defining with said housing first and second annular pressure chambers respectively adjacent to said first and second end faces whereby the fluid in said chambers urges said control face toward said face of said rotor, said member further having first and second passages respectively extending between said control face and said first and second end faces, said control face having first and second pressure fluid zones having first and second centers and respectively including the corresponding ends of said first and second passages and said first and second faces respectively having third and fourth pressure fluid zones with third and fourth centers, the diameters of said peripheral surfaces, the eccentricity of said second position, the outer diameter of said control face and the configuration of said ends of said passages in said control face being such that the distance between the axis of said control portion and said first and second centers respectively equal or closely approximate the distances between the axis of said control portion and said third and fourth centers.

2. A combination as defined in claim 1, wherein said first and third centers are located on a first line which is parallel to the axis of said control portion and said second and fourth centers are located on a second line which is parallel to the axis of said control portion.

3. A combination as defined in claim 2, wherein said first and second lines are located diametrically opposite each other with respect to the axis of said control portion.

4. A combination as defined in claim 2, wherein said face of said rotor is provided with a plurality of channels which seep along the ends of said first and second passages in said control face when said rotor relates to said thrust member.

5. A combination as defined in claim 4, wherein said rotor is provided with liquid displacing chambers communicating with said channels and further comprising liquid displacing elements movably mounted in said housing and extending into said liquid displacing chambers.

6. A combination as defined in claim 1, wherein the ends of said passages in said control face are disposed at a predetermined distance from the axis of said control portion.

7. A combination as defined in claim 1, wherein the diameter of said third peripheral surface is less than the diameter of said first or second peripheral surface and said control face is an angular face having a circular outer edge.

8. A combination as defined in claim 1, wherein said first peripheral surface has a first diameter and said control face has a second diameter, one of said first and second diameters being greater than the other thereof.

9. A combination as defined in claim 8, wherein said first diameter is greater than said second diameter.

10. A combination as defined in claim 1, wherein a portion of said second peripheral surface extends radially outwardly beyond said control face.

11. A combination as defined in claim 10, wherein said portion of said second peripheral surface is located radially inwardly of or is flush with said first peripheral surface.

12. A combination as defined in claim 1, wherein said housing comprises a one-piece portion which is provided with said socket.

13. A combination as defined in claim 1, wherein said end of at least one of said passages has an area exceeding the cross-sectional area of the remainder of said one passage.

14. A combination as defined in claim 13, wherein said end of said one passage extends beyond said remainder of said one passage as considered in the radial direction of said control portion.

15. A combination as defined in claim 1, wherein the distance (Gco) between said first center and the axis of said control portion equals

$$Gco = 2(Ro^3 - Ri^3)/3 (Ro^2 - Ri^2) \times (\sin \alpha_2 - \sin \alpha_1)/(\alpha_2 - \alpha_1)$$

wherein Ro is the radius of a circle slightly smaller than the radius of the outer edge of said control face and Ri is the radius of a circle slightly larger than the radius of the inner edge of said control face.

16. A combination as defined in claim 15, wherein the distance (gco) between said third center and the axis of said control portion equals or approximates

$$g_{co} = \int \frac{\theta \pi}{540} \left[\left(r_o - \frac{e^2}{4r_o} + \frac{e \sin \alpha}{\text{arc } \theta} - \frac{e \sin (\alpha - \theta)}{\text{arc } \theta} \right) \right. \\ \left. + \frac{e^2 \sin 2\alpha}{8r_o \text{arc } \theta} - \frac{e^2 \sin 2(\alpha - \theta)}{8r_o \text{arc } \theta} \right)^3 - r_m^3 \left] \cos \left(\alpha - \frac{\theta}{2} \right) da / \bar{K}_1 \right.$$

17. A combination as defined in claim 1, wherein the distance (Gci) between said second center and the axis of said control portion equals

$$Gci = 2(Ro^3 - Ri^3)/3 (Ro^2 - Ri^2) \times (\sin \alpha_2 - \sin \alpha_1)/(\alpha_2 - \alpha_1)$$

18. A combination as defined in claim 17, wherein the distance (gci) between said fourth center and the axis of said control portion equals or approximates

$$g_{ci} = \int \frac{\theta \pi}{540} \left[\left(r_m - \frac{e^2}{4r_m} + \frac{e \sin \alpha}{\text{arc } \theta} - \frac{e \sin (\alpha - \theta)}{\text{arc } \theta} \right) \right. \\ \left. + \frac{e^2 \sin 2\alpha}{8r_m \text{arc } \theta} - \frac{e^2 \sin 2(\alpha - \theta)}{8r_m \text{arc } \theta} \right)^3 - r_i^3 \left] \cos \left(\alpha - \frac{\theta}{2} \right) da / \bar{K}_1 \right.$$

19. A combination as defined in claim 1, wherein the area of said first or second end face equals $A_{Stz} \times fb$ wherein fb is less than 1.06 but more than 1.04 and

$$A_{Stz} = (Ro^2 - Ri^2) \alpha \pi / 4 \times 360.$$

20. A combination as defined in claim 1, wherein the area of said first end face equals

$$(ro^2 - ri^2) \pi / 4 = (Ro^2 - Ri^2) \alpha \pi / 4 \times 360 \times fb.$$

21. A combination as defined in claim 1, wherein the area of said second end face equals

$$(rm^2 - ri^2) \pi / 4 = (Ro^2 - Ri^2) \alpha \pi / 4 \times 360 \times fb.$$

22. A combination as defined in claim 1, wherein the outer diameter of said first pressure chamber exceeds the outer diameter of said control face.

23. A combination as defined in claim 1, wherein the diameter of said third peripheral surface exceeds the inner diameter of said control face.

24. A combination as defined in claim 1, wherein said control face is flat, at least in the regions surrounding said ends of said passages.

25. A combination as defined in claim 1, wherein the distance between said ends of said passages and the inner and outer edges of said control face is 1/5-1/20 inch.

26. A combination as defined in claim 1, wherein the cross-sectional area of each of said pressure chambers is 55-60 percent (plus minus 10 percent) of the effective area of said control face.

27. A combination as defined in claim 1, wherein said thrust member has an eccentric end portion whose eccentricity with respect to said control portion is different from the eccentricity of said second portion.

28. A combination as defined in claim 1, wherein said thrust member consists of two parts including a front part which constitutes said control portion and a rear part which constitutes said second and third portions.

29. A combination as defined in claim 1, wherein said thrust member has at least one seat for at least one annular sealing element.

30. A combination as defined in claim 1, wherein the diameter of said third peripheral surface exceeds the inner diameter of said control face.
